UNITED STATES PATENT OFFICE.

GEORGE B. BAKER, HERBERT B. BAKER, AND EDWARD C. BAKER, OF BROCKTON, MASSACHUSETTS.

TACK MACHINE.

Application filed August 8, 1923. Serial No. 656,411.

To all whom it may concern:

Be it known that we, GEORGE B. BAKER, HERBERT B. BAKER, and EDWARD C. BAKER, citizens of the United States of America, 5 and residents of Brockton, in the county of Plymouth and State of Massachusetts, have invented new and useful Improvements in Tack Machines, of which the following is a specification.

10 This invention pertains to tack and nail making machines and relates more particularly to means for feeding the blanks or tack strips to the cutting instrumentalities.

In our co-pending application, Serial No. 15 646,846, filed June 21, 1923, we have disclosed mechanism of a semi-automatic type applicable to existing tack and nail machines of usual design and operating automatically to present a fresh blank or tack 20 strip to the cutting instrumentalities when the old strips are consumed.

Principal objects of the present invention are to provide more positive means for feeding the blanks toward the cutting instrumentalities; to provide an improved automatic mechanism for initiating the feeding of a fresh blank; to provide improved blank presenting means; and in general to simplify the construction of the feed mechanism and to make its operation certain.

A preferred embodiment of the invention is illustrated by way of example in the accompanying drawings, in which:

Fig. 1 is a side elevation of a tack machine 35 of well known type having the present improvements applied thereto;

Fig. 2 is a fragmentary side elevation partly in section and to larger scale showing details of the blank feeding and presenting devices;

Fig. 3 is a plan view, partly in section, of the parts shown in Fig. 2;

Fig. 4 is a longitudinal vertical section of the parts shown in Fig. 2;

45 Fig. 5 is a vertical section substantially on the line 5—5 of Fig. 4;

Fig. 6 is a vertical section on the line 6—6 of Fig. 4;

50 Fig. 7 is a vertical section on the line 7—7 of Fig. 4;

Fig. 8 is a fragmentary side elevation illustrating details of construction of the blank feeding devices viewed from the side opposite to that from which Fig. 2 is taken;

55 Fig. 9 is a fragmentary plan view partly

in horizontal section illustrating details of the right-hand portion of the structure shown in Fig. 2;

Fig. 10 is a vertical section on the line 10—10 of Fig. 4;

Figs. 11 and 12 are sections similar to Fig. 10 illustrating the employment of spacers of different dimensions;

Fig. 13 is a fragmentary side elevation showing a modified form of feed mechanism; and

Fig. 14 is a fragmentary side elevation to large scale showing details of a blank clamping device.

Referring to the drawings, 1 indicates the 70 supporting frame of a tack machine of usual construction. This frame is provided with bearings for a main shaft having a hand wheel 2 and also supports an anvil block 3 comprising the fixed or ledger blade 4, 75 the latter being provided with a diagonal cutting edge in the usual manner. The main shaft is furnished with the usual cams, cranks, and other devices for actuating the operative parts of the machine including 80 the movable cutters 5 and 6 and the movable gage 7.

Resilient guards 8 and 9 are supported 85 upon the anvil block 3 in suitable brackets 10 and 11 respectively as is usual in machines of this character, the guards cooperating with the blank to position it properly for the action of the cutters. A table 12 projects from the upper part of the frame and is provided with a relatively narrow 90 elongate extension 13.

The usual cylindrical tubular blank presenting barrel 14 is employed for guiding the blank strips toward the cutters. This barrel inclines downwardly toward the anvil 95 and is furnished adjacent to its upper end with a spherical collar 15 which turns freely in a cup bearing 16 carried by a bracket 17 mounted on the extension member 13.

At a suitable point intermediate the 100 bracket 17 and the anvil block, posts 18 and 19 are secured in a forwardly and upwardly extending arm 20 carried by a block 21 secured to the table 12. A cross bar 22 is secured to the upper ends of the posts 18 and 19 by means of bolts 23. Preferably this bar is provided with fins 24 which engage suitable slots in the upper ends of the posts to maintain the posts in exact parallelism. The under surface of the bar 22 is furnished 110

with a depending lug 25 for positioning a coil spring 26 interposed between the bar 22 and a yoke 27 guided by the posts 18 and 19 to slide vertically and having a concave 5 lower surface which rests upon the top of the barrel 14. This spring pressed yoke tends to hold the barrel downwardly with its free lower extremity engaging the upper surface of the anvil block but permits the 10 barrel to rise slightly as it is oscillated during the operation of the machine. By removing the bolts 23 the bar 22 may be raised, thus permitting the barrel to be lifted from between posts 18 and 19 and swung to one 15 side away from the cutting instrumentalities to permit sharpening or adjustment of the latter.

Straps 28 and 29 are employed for oscillating the barrel as is usual in machines of 20 this type. These straps are wound in opposite directions about the barrel and their lower ends are secured to oppositely extending arms of a lever 30 fulcrumed at 31 upon the extension 13. This lever is rocked by 25 means of a link 32 actuated from the main shaft of the machine and provided with a normally fixed block 33 having a notch for the reception of a stud or pin 34 projecting from a depending arm of the lever 30. The 30 stud 34 is normally held in engagement with the block 33 by the arm 35 of a counter-weighted lever 36 carried by an adjustable block 37 mounted on the link 32.

A yoke 38 carrying a forwardly extending 35 guideway 39 is pivotally secured to the bracket 17. This yoke has the depending lug 38^a bearing against an adjustable set screw 40 which permits the yoke with its guide member 39 to be adjusted angularly.

40 The guide member 39 is normally disposed parallel to the axis of the barrel 14 and is furnished with a suitable slot or track along which a block 41 may slide. This block is preferably provided with a handle 41^a and 45 with a transverse bore in which a short shaft 42 is journaled. The axis of the shaft normally aligns with that of the barrel and the lower end of the shaft is provided with a projection 42 constituting a fixed jaw with 50 which a resilient jaw 43 cooperates. The jaw 43 preferably consists of a flat spring secured at one end to the shaft. The clamp comprising the jaws 44 and 43 is adapted 55 to grip the upper end of a reserve blank 44 whose lower end is disposed just within the upper end of the barrel 14. Ordinarily the central part of the blank needs no support.

A flexible cord or chain 45 is connected at 60 one end to the block 41 and extends downwardly along the guideway 39 to the pulley 46, and thence down and under the pulley 47 supporting the weight 48, the opposite end 49 of the cord or chain being attached to a convenient part of the extension 13. 65 The block 41 is normally held at the upper

end of the guide member 39 by means of a latch 50 which engages the upper end of the vertically movable core of a solenoid 51, the arrangement being such that upon energization of the coils of the solenoid the core is 70 retracted and the latch 50 is released to permit the weight 48 to pull the block 41 down the guideway 39. Any other suitable type of electrically releasable latch mechanism may be substituted for that herein shown. 75

The barrel is furnished at its lower end with an extension comprising the sleeve member 52 having a peripheral rib 53 having opposed conical sockets for the reception of the conical ends of pivot pins 54 and 55 respectively. These pivot pins have threaded engagement with diametrically opposite radial openings in a flat ring 56 normally concentric with the sleeve and constituting a lever capable of rocking relatively to the sleeve. Cams 57 and 58 are disposed upon opposite sides respectively of the ring 56, one of the cams as for example the cam 57 being adjustably mounted upon the ring by means of a pin 59 entering a slot 60 in the ring. The cams 57 and 58 are preferably disposed substantially 90° away from the axis of oscillation of the ring and diametrically opposite to one another. At a point adjacent to one of the cams the peripheral portion of the ring is cut away to provide a shoulder 61 substantially perpendicular to the axis of oscillation of the ring, its purpose being described hereinafter. 90

95 At its lower end the sleeve 52 merges into a box-like casing 62 which is open at top and bottom and which has openings 63 and 64 aligning with the passage through the barrel 14. Pins 65 and 66 project inwardly from opposite walls of the casing 62 and into the opening 63. The inner ends of these pins are beveled to provide a converging guide passage for properly directing the blank or nail strip as it enters the box or casing. 100

105 A shaft 67 is journaled in fixed bearing openings in the side walls of the box 62 and is provided at its central part with a roller comprising spaced discs 68 whose peripheral surfaces are preferably knurled. A second shaft 69 parallel to the shaft 67 is arranged to turn in vertically elongate bearing openings in the side walls of box or casing 62. This shaft also carries a roller comprising a pair of spaced knurled discs 70 which cooperate with the discs 68 in feeding a blank strip. 110

115 A yoke 71 extends transversely across the box above the shaft 69 and is provided with depending legs notched at their lower ends to engage the shaft 69. The yoke 71 is provided with the upwardly projecting pin 72 at its central part which passes through an opening in a contact supporting lever 74 whose rear extremity is seated loosely in an 120 125 130

opening in a bracket 73 secured to the casing 62. The top of the casing is provided with a cover 76 having legs 77 which rest upon the upper edge of the casing and which is secured to the latter by screws 76^a. This cover is furnished with a cavity for the reception of a spring 78 which bears upon the upper surface of the lever 74 and whose tension may be adjusted by means of a set 10 screw 79.

The forward free extremity of the lever 74 is provided with an adjustable contact pin 80 engageable with a metallic ring 80^a surrounding the sleeve 52 and insulated therefrom by suitable insulating material 81. A metallic conductor 82 extends forwardly along the sleeve 52 from the ring 80^a and through a slot in the rib 53 and is connected to an annular plate or washer 83 secured to the end of the sleeve 52. The conductor 82 and the washer 83 are insulated from the sleeve 52 as indicated at 84.

A resilient contact finger 86 bears at all times against the outer surface of the washer 83. This finger is secured to the bracket 20 but is insulated therefrom and a conductor wire 87 leads from the finger 86 to one terminal of the solenoid 51. A battery 88, or other suitable source of electrical energy may be interposed at a desired point in the conductor 87. A second conductor 89 is grounded upon the frame of the machine at a suitable point and extends to the other terminal of the solenoid 51.

The upper part of the block 21 is furnished with an undercut or dove-tail slot 90 for the reception of the heads of bolts 91 and 92. These bolts are locked in adjusted position by means of nuts 93 bearing upon the upper surface of the block 21. Anti-friction rollers 94 and 95 are mounted to turn upon the upper projecting ends of the bolts 91 and 92 respectively, being held in position thereon by short bolts 96. The rollers 94 and 95 are so disposed that they lie on opposite sides of the plane of the ring 56 and are thus adapted for engagement by the cams 58 and 57 respectively.

One end of a link 97 is pivotally secured at 98 to the shoulder 61 of the ring 56 and its opposite end is pivotally connected by a bolt 99 to the free extremity of a lever 100 journaled to turn freely upon one end of the shaft 67 which projects outwardly through the wall of the casing 62. A ratchet wheel 101 is also mounted upon the projecting end of the shaft 67 but is fixed to the latter. Pawl 102 is pivotally secured by means of a bolt 102^a to the lever 100 and is normally kept in engagement with the teeth of the ratchet wheel 101 by a coil spring 103 attached at one end to the pawl and at the other to a pin 104 projecting from the sleeve 102.

The lower part of the casing or box 62

projects rearwardly to provide a supporting bracket 105 upon which the lower plate 106 of a nose piece is mounted. This nose piece also includes the upper plate 107 and the spacer members 108 and 109 which hold the 70 plates 106 and 107 in vertically spaced position. The plates 106 and 107 and the spacers 108 and 109 are held in assembled relation by means of bolts 110 and 111, certain of these bolts entering threaded openings in 75 the bracket 105 to secure the nose piece to the box 62. Preferably the plates 106 and 107 have forwardly projecting tongues 106^a and 107^a respectively which extend into the grooves between the discs forming the upper 80 and lower feed rolls.

As indicated in Figs. 11 and 12 the spacer members 108 and 109 may be of different widths or thicknesses to provide a blank guiding channel of any desired cross sectional form. To permit the feeding mechanism to handle blanks of different widths or thicknesses it is contemplated that the machine will be provided with a plurality of interchangeable sets of such spacer members by means of which the guide channel 85 may be adapted to the particular size of blank which it is desired to feed.

In Fig. 13 a modified form of drive mechanism for the feed rollers is illustrated. In this figure the barrel proper is indicated at 14^a, the sleeve at 52^a, and the casing or box at 62^a. The casing is provided with feed rollers (not shown) the lowermost of which has a projecting shaft 67^a furnished with a ratchet wheel 101^a. The lever 100^a is pivoted upon the shaft 67^a and is provided with the pivoted pawl 102^a engaging the ratchet wheel. A spring 103^a normally holds the pawl in operative relation to the wheel. The lever 100^a is furnished with a lug 114 which contacts with the end of the slide bar 114 mounted in suitable guide brackets 116 carried by the box. The opposite end of the bar 115 is so disposed as to contact with either of a pair of cams 117 mounted upon the posts 18 and 19 respectively.

The operation of the machine is substantially as follows, it being assumed that the parts initially occupy the position shown in Fig. 1 and that the main shaft is rotating and that the barrel 14 is oscillating.

As indicated in Fig. 4 a blank or tack strip 113 is passing between the feed rollers comprising the discs 68 and 70 and between the guiding tongues 106^a and 107^a into the channel in the nose piece which rests upon the upper surface of the anvil. The end of the tack strip projects beyond the end of the nose piece and at each stroke of the cutters the projecting portion of the strip is cut off to form a tack all in the usual manner. The presence of the blank between the feed rollers causes the upper roll to be lifted in opposition to the spring 78 so that the con-

tact pin 80 is normally held away from the ring 80^a. The ring 56 oscillates with the barrel and thus the cams 57 and 58 are brought alternately into contact with the 5 rollers 95 and 94 respectively. At each such contact the ring 56 is so rocked as to swing the lever 100 with its pawl to move the ratchet wheel 101 a step forward. The shaft 67 is thus intermittently driven and as this 10 shaft is connected to the upper shaft 69 by means of intermeshing gears 206 the upper shaft is also positively driven. During the intervals between contacts of the cams 57 and 58 with their rollers spring 103 retracts the 15 lever 101 to cause the pawl 102 to engage an advanced tooth of the ratchet. The feed rollers thus feed the tack strip forward intermittently and at substantially the rate at which it is consumed.

20 The feeding of the blank or tack strip thus continues until the end of the strip passes from beneath the upper roller 70 when the latter immediately drops under the action of the spring 78. This causes the contact pin 80 to engage the ring 80^a completing the circuit through the solenoid and releasing the latch 50. The block 41 is immediately pulled down the guideway 39 by the weight 48 and as the upper end of the 25 fresh or replenishing tack strip or blank 44 is held between the jaws 42 and 43 the fresh strip is fed quickly down into the barrel until its lower end enters between the rotating rollers 68 and 70. As soon as the 30 rollers grip the strip they begin to feed it forward and the upper roll is thus forced upwardly to its normal position breaking the circuit through the solenoid. The descent of the block 41 is readily observed by the operator by reason of the prominence of the upstanding handle 41^a and as soon as convenient the operator pulls the block 41 back to its normal position where it is 35 automatically latched. The operator then inserts the end of the fresh tack strip into the upper end of the barrel 14, forces its opposite end between the jaws 42 and 43, and the machine is ready for the repetition of the above sequence of operation.

40 The device shown in Fig. 13 operates in substantially the same manner as that previously described except that in this case the 45 rocking ring or lever 56 is dispensed with and the actuating cams are fixed. As the 50 barrel oscillates the end of the pin 15 engages one of the cams 117 and then the other so that the lever 100^a is intermittently oscillated thereby stepping the ratchet wheel 101 forward to actuate the feed rollers.

55 With the mechanism above described blanks are fed in such close succession that substantially no time need be wasted and the formation of waste ends or butts is almost entirely eliminated. Fresh blanks may be 60 inserted in a fraction of the time neces-

sary in feed mechanisms of the usual type while the entire structure is of simple form and may readily be attached to existing machines without any substantial alterations in the latter.

70

We claim:

1. A tack machine comprising movable blank presenting and feeding means including a bodily movable feed roll, blank replenishing devices, and means controlling the replenishing devices, the operation of said controlling means being determined by the position of the bodily movable feed roll.

75

2. A tack machine having blank replenishing means including an electro-magnetic device, and blank feeding devices comprising a pair of opposed feed rolls, one of said rolls being bodily movable toward and from the other, an electrical contact element movable in consonance with the bodily movement of said roll, and a relatively fixed contact element cooperable with said movable contact element, said elements constituting terminals of an electrical circuit including the windings of said electro-magnetic device.

80

3. A tack machine having cutting instrumentalities, blank presenting means, and blank replenishing means including an electro-magnetic device, a bodily movable feed roll supported by the presenting means and normally positioned by engagement with a blank on its way to the cutting instrumentalities, and an electrical circuit comprising normally spaced terminals and including the windings of said electro-magnetic device, one of said terminals being movable with the feed roll, said movable terminal being constructed and arranged to complete the electrical circuit through the terminals upon movement of the feed roll due to substantial exhaustion of the blank in the presenting means.

85

4. A tack machine comprising blank replenishing means including an electro-magnetic device, an oscillating barrel, a bodily movable blank feeding roll supported thereby, a relatively fixed electrical contact carried by the barrel, a movable contact connected with the feed roll, and resilient means tending so to move the roll when not engaging a blank as to bring the contacts into engagement and complete an electrical circuit between them, said circuit including the windings of said electro-magnetic device.

90

5. A tack machine comprising a blank replenishing mechanism including an electro-magnetic device, an oscillating barrel, a bodily movable feed roll supported thereby, an electrical contact member movable with said feed roll, an insulated contact fixed relatively to the barrel and engageable by the first contact, an insulated ring carried by the barrel electrically connected to the

100

105

110

115

120

125

130

fixed contact, and a resilient finger engaging the ring in all positions of the barrel and constituting an element of an electrical circuit, said circuit including the windings of said electro-magnetic device.

6. A tack machine comprising a blank replenishing mechanism including an electro-magnetic device, an oscillating barrel, a casing secured to one end of the barrel, a feed roll mounted in fixed bearings in the casing, a cooperating feed roll mounted to move bodily toward and from the first roll, a spring tending to move the second roll toward the first roll, a lever movable in consonance with the bodily movable roll, an electrical contact element carried by the lever, and a cooperating contact element supported by the barrel, said contact elements and the windings of the electro-magnetic device being included in an electrical circuit.

7. A tack machine comprising a blank presenting barrel, means for inserting a reserve blank into the barrel, a releasable retaining device normally preventing operation of the inserting means, electro-magnetic means for rendering the retaining device inoperative, a bodily movable feed roll supported by the barrel, a contact element movable with the feed roll, and a second contact element engageable by the first upon failure of the roll to engage a blank, engagement of said contact elements completing an electrical circuit to energize the electro-magnetic means.

8. A tack machine having tack forming and blank presenting means, replenishing devices, a releasable latch for determining operation of the replenishing devices, a bodily movable feed roll maintained in a predetermined position by a blank in the presenting means, means tending to move the roll away from such position, and means to release the latch, said releasing means responding to movement of the feed roll from said predetermined position due to substantial exhaustion of a blank from the presenting means and thereby releasing the latch.

9. A tack machine comprising a blank presenting barrel, means for inserting a reserve blank into the barrel, an electrically releasable latch normally preventing operation of the blank inserting means, a pair of feed rolls supported by the barrel, one roll being bodily movable relatively to the other, and electrical contact means actuatable upon movement of the bodily movable roll toward the other roll in the absence of a blank between them to complete an electrical circuit whereby to release the latch and permit insertion of the reserve blank into the barrel.

10. A tack machine comprising an oscillating barrel, blank replenishing means,

controlling means for the replenishing means including an electrical circuit, a bodily movable feed roll supported by the barrel and normally held in predetermined position by engagement with a blank, an electrical contact movable with the roll, a second contact fixedly mounted upon the barrel but insulated therefrom, an insulated ring mounted on the barrel connected with the fixed contact and a resilient finger bearing upon the ring and connected to one terminal of the circuit, the other terminal thereof being electrically connected to the barrel.

11. A tack machine comprising a blank replenishing mechanism including a latch and a solenoid for releasing it, an oscillating barrel, a pair of shafts supported thereby, each being provided with a feed roll, one shaft being bodily movable relatively to the other, a yoke supported by the movable shaft, a lever bearing upon the yoke, a spring acting upon the yoke normally tending to urge the bodily movable shaft toward the other shaft, the shafts normally being held apart by the interposition of a blank between the feed rolls, an electrical contact carried by the lever, and a second contact engageable by the first upon approach of the feed rolls due to absence of a blank between them, said contacts and the windings of the solenoid being included in the same electrical circuit.

12. A tack machine comprising a blank replenishing mechanism including an electro-magnetic device, an oscillating barrel, a casing secured to the barrel, a pair of shafts journaled in the casing, one shaft being movable bodily toward and from the other and each being provided with a feed roll, a yoke supported by the bodily movable shaft, a pin projecting from the top of the yoke, a lever fulcrumed adjacent to one end bearing upon the top of the yoke and having an opening for the reception of the pin, a spring bearing upon the top of the lever, an electrical contact element carried by the free end of the lever, and a cooperating contact carried by but insulated from the barrel, said contact elements and the windings of the electro-magnetic device forming parts of the same electrical circuit.

13. A tack machine having an oscillating barrel and blank replenishing means comprising a sliding member provided with a journal opening, a shaft turning freely in said opening and normally aligned with the axis of the barrel, a fixed jaw carried by the shaft, and a flat spring cooperable with the fixed jaw to grip the end of a blank.

14. A tack machine having an oscillating barrel and blank replenishing means comprising a member guided to slide toward and from the open end of the barrel and

- constructed and arranged to support one end of a blank having its opposite end supported within the end of the barrel and with its central portion unsupported.
15. A tack machine having an oscillating barrel and blank replenishing means comprising a member movable toward and from the end of the barrel, and clamping means carried by said member arranged resiliently 10 to grip and hold one end of a blank in line with the axis of the barrel, the opposite end of the strip being supported within the barrel, the central portion of the blank being unsupported.
16. A tack machine comprising an anvil, an oscillating barrel provided at one end with a nose piece normally resting upon the barrel the opposite end of the barrel being supported by a ball and cup bearing, parallel posts disposed upon opposite sides of the barrel intermediate its ends, a cross bar removably secured to the upper ends of the posts, a yoke guided for vertical movement by engagement with the posts and having 25 a concave under surface normally bearing upon the barrel, and a compression spring interposed between the yoke and cross bar.
17. A tack machine comprising an oscillating barrel, having a sleeve-like extension 30 at one end, said extension terminating in a box-like casing, a pair of feed rolls mounted on the casing, a lever device pivotally mounted upon the extension, means for 35 rocking the lever device as the barrel oscillates, and connections between the lever device and feed rolls for turning the latter step by step as the lever is rocked.
18. A tack machine comprising cutting 40 instrumentalities and means for feeding a blank to the cutting instrumentalities comprising an oscillating barrel supporting a pair of feed rolls, a ratchet wheel secured to one of the rolls, a pawl engageable with the ratchet wheel for turning it, a lever device pivotally supported by the barrel, a cam carried by the lever device, means connecting the lever device with the pawl, and a relatively fixed abutment arranged in the path of the cam as the latter turns with 50 the barrel whereby to swing the lever device and actuate the pawl.
19. A tack machine comprising an oscillating barrel, a pair of feed rolls carried thereby, one of the feed rolls having a ratchet wheel secured thereto, a pawl for turning the ratchet wheel, a lever device pivotally supported by the barrel to oscillate about an axis transverse to that of the barrel, a link connecting the lever device 55 with the pawl, a cam mounted at each end of said lever device, and means fixed relatively to the barrel for engagement with the respective cams as the barrel oscillates whereby to actuate the feed rolls.
20. A tack machine having blank feeding 60 means comprising an oscillating barrel, a pair of feed rolls supported thereon, a ring concentric with the barrel and supported to oscillate about an axis transverse to that of the barrel, a cam mounted upon each face 70 of the ring, means engageable with the respective cams as the barrel oscillates for rocking the ring, and means for transmitting movement from the ring to the feed rolls.
21. A tack machine comprising an oscillating barrel provided at one end with an extension comprising a sleeve terminating in a casing, a pair of feed rolls journaled in the casing, a ratchet wheel fixed to one 80 roll, a pawl cooperable with the ratchet wheel, a ring surrounding the sleeve, diametrically opposed pivot members connecting the ring with the sleeve, a link connecting the ring with the pawl, and means for 85 transmitting movement from the ring to the feed rolls as the barrel oscillates.
22. A tack machine having blank feeding means comprising an oscillating barrel, a pair of feed rolls supported thereby, a ring concentric with the barrel, diametrically opposed pivot members supporting the ring to rock about an axis transverse to that of the barrel, a cam secured to either face of the ring, the cams being substantially diametrically opposite one another, spaced elements engageable with the respective cams as the barrel oscillates whereby to rock the ring, and connections between the ring and feed rolls for actuating the latter.
23. A tack machine comprising an oscillating barrel having a sleeve adjacent to one of the ends, said sleeve having a peripheral rib provided at diametrically opposite points with socket openings, a ring concentric with 105 the sleeve, radially arranged pivot pins projecting from the inner periphery of the ring into the respective socket openings, a pair of feed rolls supported by the sleeve, means for 110 rocking the ring about the axis defined by the pivot pins as the barrel oscillates, and means transmitting movement from the ring to the feed rolls.
24. A tack machine having blank feeding 115 means comprising an oscillating barrel, a pair of feed rolls supported thereby, a lever device carried by the barrel arranged to rock about an axis transverse to that of the barrel, a member projecting from the lever device at either end thereof, the respective 120 members being disposed at opposite sides of the lever, a pair of spaced rolls mounted upon a fixed support, each roll lying in the path of one of said projecting members as the barrel oscillates, and means for transmitting movement from the lever to the feed rolls.
25. A tack machine comprising an oscillating barrel terminating in a casing, feed rolls mounted in the casing, the latter hav- 125 130

- ing entrance and exit openings aligned with the axis of the barrel, and devices projecting from opposite sides of the casing into the entrance opening to center a blank approaching the rolls.
26. A tack machine comprising an oscillating barrel, a pair of feed rolls supported thereby, and a pair of oppositely directed pins arranged in advance of the feed rolls, said pins having beveled ends providing a flaring guideway for centering a blank in approaching the rolls.
27. A tack machine comprising an oscillating barrel and a pair of feed rolls supported thereby, each roll consisting of a plurality of axially spaced members having knurled peripheral surfaces.
28. A tack machine having an oscillating barrel provided with a nose piece, the latter comprising upper and lower spaced plates providing a guide passage therebetween, a pair of feed rolls supported by the barrel, each roll consisting of a plurality of spaced members, and guide tongues projecting from the ends of the respective plates and extending into the spaces between the members composing each roll.
29. A tack machine having an oscillating barrel provided with a nose piece comprising upper and lower spaced plates providing a guide passage between them, a pair of feed rolls supported by the barrel, the feed rolls each having a peripheral groove, and a guide tongue forming an integral continuation of each plate, the guide tongues of the two plates extending into the grooves of the respective rolls.
30. A tack machine having an oscillating barrel provided with a nose piece, the nose piece comprising upper and lower substantially parallel elongate plates and a pair of spacer members removably secured between the plates and spaced from each other to provide a guide passage extending longitudinally of the nose piece.
31. Mechanism of the class described having a blank receiving barrel provided with a nose piece, the nose piece comprising a bottom plate, a top plate, spacer means interposed between the plates, and means for removably retaining the plates and spacer means in assembled relation.
32. Mechanism of the class described having a barrel provided with a blank presenting nose piece, the nose piece comprising upper and lower members and interchangeable spacer elements interposable between said members to provide a variable blank guiding passage to accommodate blanks of different cross sectional area.

Signed by us at Brockton, Mass., this second day of August 1923.
